US0D1007486S

(12) **United States Design Patent** (10) Patent No.: **US D1,007,486 S**
 (45) Date of Patent: ** Dec. 12, 2023

(54) **HEADPHONE STAND WITH CHARGING PORT**

(71) Applicant: **Xiaoqian Xie**, Qingyuan (CN)

(72) Inventor: **Xiaoqian Xie**, Qingyuan (CN)

(73) Assignee: **Xiaoqian Xie**, Qingyuan (CN)

(**) Term: **15 Years**

(21) Appl. No.: **29/878,446**

(22) Filed: **Jun. 21, 2023**

(51) LOC (14) Cl. **14-01**

(52) U.S. Cl.

USPC **D14/224**; D13/108

(57) **CLAIM**

The ornamental design for a headphone stand with charging port, as shown and described.

DESCRIPTION

FIG. 1 is a top perspective view of a headphone stand with charging port, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the headphone stand with charging port, which form no part of the claimed design.

1 Claim, 8 Drawing Sheets
